UNITED STATES PATENT OFFICE

ERNEST SHEPARD, OF CONCEPTION JUNCTION, MISSOURI

LANTERN BURNER

Application filed May 7, 1929. Serial No. 361,193.

The object of my invention is to provide a lantern burner of simple, durable and comparatively inexpensive construction.

More particularly it is my object to provide a burner which may be used on any type of oil burning lantern or lamp, but which is especially adapted to signal lanterns which are used by railroad men for signalling purposes. In this connection such a signal lantern is oftentimes swung and jerked from one position to another and it has been my object to provide a burner so constructed that it will burn kerosene or the like without smoking and without fanning or jerking out of the flame.

Still another object is to provide a specially designed shield for the burner which encircles the upper end of the wick tube in such a way that air is properly distributed to the various parts of the flame, in such a manner as to form a good flame of desirable shape and yet eliminates extinguishment of the flame caused by sudden movements of the lantern.

Still a further object is to provide a wick cylinder in which the wick may be folded so that the wick does not move around in the oil container of the burner, and the lower end of the wick is always kept in a position close to the bottom of the oil container so as to use the last of the oil therein when the oil gets to a low point.

Still a further object is to provide an adjustment for the burner with a pair of elements adapted to engage the adjustment to prevent easy movement thereof.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a signal lantern in which my burner may be applied and in connection with which it is illustrated.

Figure 2 is a side elevation of the burner.

Figure 3 is a plan view of the same.

Figure 4 is a vertical sectional view on the line 4—4 of Figure 2.

Figure 5 is a vertical section view on the line 5—5 of Figure 3; and

Figure 6 is an enlarged section view on the line 6—6 of Figure 2.

On the accompanying drawings I have used the reference character A to indicate generally a lantern. The lantern A is usually provided with an oil container 10 having a screw-threaded neck in which a burner is mounted. My improved type of burner is indicated generally by the reference character B and has a screw-threaded neck 12 adapted to screw into the container 10. The burner B is provided with a head 14 through which a flattened wick tube 16 extends. Below the neck 12 the burner B terminates in a wick cylinder 18. The lower end of the wick tube 16 projects into the upper end of the wick cylinder 18.

The wick cylinder 18 has a closure member 20 at its lower end. The member 20 is provided with a flattened sleeve 22 through which the lower end of a wick 24 may extend. The upper end of the wick 24 as clearly shown in Figure 4, terminates at the dotted position indicated by the reference numeral 26. The wick 24 may be adjusted relative to the wick tube 16 by an adjusting shaft 28 carrying spur wheels 30.

Easy rotation of the adjusting shaft 28 is prevented by means of friction elements 32 and 34. The amount of friction may be adjusted by adjusting the clamp screws 36. The member 32 is carried on pins 38 projecting from the burner B.

In connection with the upper end of the flat wick tube 16 I provide a shield C comprising supporting portions 40 extending upwardly from the burner head 14 and a shield portion encircling the upper end of the wick tube 16. The shield portion has inwardly directed parts 42 terminated in outwardly flared parts 44 adjacent the side edge of the wick tube 16. The shield portions C have inwardly flared parts 46 adjacent the flat sides of the wick tube 16.

The wick tube 16 is made up of flat side portions and narrow end portions which are concaved downwardly as clearly shown in Figures 4 and 5 of the drawings. The

purpose of this is so that the wick 24 can be easily trimmed after becoming charred by merely running the end of a match lengthwise across the end of the tube and thereby 5 depressing the upper end of the wick from side edge to side edge thereof.

I will now describe the function of the various parts of my improved type of burner, thus far described. The wick cylinder 18 10 is adapted to receive the portion of the wick 24 intermediate the ends thereof in folded formation as clearly shown in Figure 4. This allows the short lower end of the wick to project from the cylinder 18 for collecting the 15 oil from the container. The intermediate portion of the wick therefore is not swung around inside of the container 10, but is confined against such swinging movement. This construction insures that the lower end of 7.20 the wick will always remain adjacent the bottom of the container 10, which is especially desirable when there is but little oil left in the container.

I have found that encasing the wick in the 25 cylinder 18 enables me to burn kerosene in the burner which has heretofore been objectionable because of kerosene being so thin that it splashes in the container 10. The wick 24 may be easily inserted in position by removing the closure member 20, whereupon 30 the lower end of the wick may be inserted through the tube 22 and the closure member replaced. Arranging the wick within the cylinder also prevents twisting of the wick 35 when screwing the wick into the container 10.

The shield C has outflared portions 44 and inflared portions 46 as illustrated on the drawings for the specific purpose of causing the flame 48 to assume a desirable formation as shown on the drawings. The flame does not flare out and come to a sharp point, but stops abruptly, so that a flame which is thick clear to the upper end of the flame results. The outflared portions 44 form pockets at the end of the frame through which the combustion of the flame passes. The inflared portions 46 distribute the upward draft of air caused by the heat of the flame in the proper manner for causing the flame to assume a desirable formation. The shield portions being arranged as they are prevent fanning out or choking of the flame when the lantern is swung or when it is jerked up and down or when it is otherwise moved suddenly.

Some changes may be made in the construction and arrangement of my device without departing from the real spirit and purpose of my invention, and it is my intention to cover by my claims, any modified forms of structure or use of mechanical equivalents, which may be reasonably included within their 65 scope.

I claim as my invention:

1. In a burner of the character disclosed, a flattened wick tube, a shield therefor surrounding the upper end of the wick tube and spaced therefrom, said shield having an outwardly flared portion adjacent an end edge of the wick tube and an inwardly flared portion adjacent a flat side of the wick tube for causing the flame from a wick in the wick tube to assume a desired formation, said shield being split between said partitions. 70 75

2. In a burner of the character disclosed, a flattened wick tube, a shield therefor surrounding the upper end of the wick tube and spaced therefrom, said shield having notches in the sides thereof extending down from the top edge of the shield and located adjacent the ends of the wick tube, the side portions of the shield between the notches being inflared and the end portions of the shield 30 35 between the notches being outflared.

3. In a lantern burner, a flattened wick tube, a shield therearound comprising flattened sides parallel with and spaced from the sides of said wick tube and having air admission openings therethrough, said shield further comprising imperforate ends spaced from the ends of said wick tube and having inwardly directed portions adjacent the top of the wick tube and outwardly flared portions above the upper edge of the wick tube. 40 45 50

4. In a burner of the character disclosed, a flattened wick tube, a wick therein, an adjusting shaft adjacent said tube, a spur wheel on said shaft for engaging said wick to move the same longitudinally when the shaft is rotated, means for imposing friction on said shaft to prevent easy rotation thereof, said means comprising a pair of engaging elements between which said shaft is arranged; 55 screws associated with said elements for drawing them toward each other and supporting rods for said engaging elements, said rods extending from and supported by said burner and said elements having sleeve portions positioned on said rods. 100 105 110

ERNEST SHEPARD.
